The ornamental design for a distributor for electronic devices, as shown and described.

DESCRIPTION

FIG. 1 is a perspective view of a first embodiment of a distributor for electronic devices showing my new design; FIG. 2 is a top plan view thereof;

FIG. 3 is a front elevational view thereof;

FIG. 4 is a right side elevational view thereof, a left side elevational view thereof being mirror image;

FIG. 5 is a bottom plan view thereof;

FIG. 6 is a rear elevational view thereof;

FIG. 7 is a perspective view of a second embodiment of a distributor for electronic devices showing my new design; FIG. 8 is a top plan view of the embodiment of FIG. 7;

FIG. 9 is a front elevational view of the embodiment of FIG. 7;

FIG. 10 is a right side elevational view of the embodiment of FIG. 7, a left side elevational view of the embodiment of FIG. 7 being mirror image;

FIG. 11 is a bottom plan view of the embodiment of FIG. 8; and,

FIG. 12 is a rear elevational view of the embodiment of FIG. 7.
